BOX MAGAZINE FOR AUTOMATIC LOADING FIREARMS

Fritz Herlach and Theodor Rakula, Solethurn, Switzerland, assignors to Waffenfabrik Solethurn A.-G., Solethurn, Switzerland, a corporation of Switzerland

Application July 27, 1933, Serial No. 682,513
In Switzerland June 16, 1933

2 Claims. (Cl. 89—33)

The invention relates to a further modification of the box magazine for automatic-loading firearms described and claimed in our co-pending application Ser. No. 666,598. According to this 5 co-pending application the magazine is provided with a removable upper side or lid, preferably in the form of a hinged lid, so as to permit the insertion of a packet of cartridges, and with a tension lever for returning the spring-controlled 10 feeder to its tensioned position. The invention provides an improvement in the mode of operation of the magazine while the weapon is being fired, and provides in particular means for reducing the friction of the cartridges and feeder 15 in order to ensure in a satisfactory manner the supply of cartridges from the magazine while in operation.

The invention is illustrated in the accompanying drawing which shows by way of example a 20 magazine constructed according to the invention.

Fig. 1 is a perspective view of the magazine in closed condition, attached to the firearm;

Fig. 2 is a similar view showing the magazine open.

Fig. 3 is a longitudinal section with the cover raised, taken on line III—III of Fig. 1; and

Fig. 4 is a cross section taken on line IV—IV of Fig. 3.

The magazine frame or belt 2, the upper side 30 of which is constructed as a hinged lid, according to the present invention, has its cartridge supporting plate, which is already provided with openings 61 and 21 for the removal of empty cartridge clips or for the passage of a feeder-projection 20, further cut away to such an extent that narrow retaining strips 19 (Fig. 2) remain extending longitudinally of the magazine. These then form narrow slide bars on which rest the cartridges of a packet of cartridges inserted 35 in the magazine. By this means the friction of the cartridges thrust forward in their clips by the feeder 16 in the magazine to the interior of the weapon, is so reduced that even in the case of an accumulation of foreign matter no stoppages of the feeding occur and the thrust of the feeder spring 27 is always sufficient to thrust the cartridges along satisfactorily in the direction of the mouth of the magazine. Any dirt which may have found its way in, which on the 40 operation of the magazine is brushed off the cartridges and the feeder and forced aside, escapes through the openings in the base without having a stopping or jamming effect.

Also, in order to prevent as much as possible 45 the interior of the magazine from becoming dirty,

the lower side of the magazine is advantageously closed by a lid. The latter is integral with the feeder tension lever 26, 28 which for this purpose is broadened out plate-wise. Thus there is provided a lid adapted to pivot about the front or outer magazine pin 29, and having an upturned curved front edge 26 co-operating with the feeder projection 29 which protrudes at the bottom of the magazine through the slot 21 to return the feeder to the tensioned position. For 10 this purpose the feeder projection 20, guided in the slot 21 of the cartridge supporting plate 70, is provided with a roller 25 against which the inside of the curved front edge 26 acts and moves the feeder backwards, when the lid-forming lever 15 26, 28 is drawn in the opened position (Fig. 2). A spiral spring 29a in the lug 29 automatically returns the lid-lever 26 and holds it in its initial position as shown in Figs. 1 and 4.

A spring 27 is fixed and supported in this feeder 20 16 by bent members 30 in the latter; pins 31 and 32 fixed to the end plate 3 prevent the outer end of the spring from springing out, when the lever 11 is open.

The end plate 3 is provided with a recess 33 in 25 which, on a bolt 34, a double armed latch 35 is mounted and held by a spring 36 supported against the end plate 3 in its normal position, in which it rests with its surface 37 against the end plate 3 of the magazine.

When the feeder 16 is withdrawn an inclined surface 38 of the projection 29 comes into contact with the projection 39 on the lower arm of the latch 35. The latter is thereby swung downwards against the pressure of its spring 36 and 35 the latch nose 43 releases the cover 11, which under the action of its spring 15 springs up into the open position as shown in Figs. 2 and 4. In consequence the projection 39 engages behind the rear shoulder of the inclined surface 38 of the 40 feeder 16 and holds it thus in the refilling position for the magazine. Then the tensioning lever 16 is released and returns by the spring 29a in the position closing the bottom of the magazine. A cartridge pack is filled in the magazine 45 and the cover 11 closed. This turns the latch 35, whose projection 39 disengages thereby the feeder 16 which is ready to move the cartridges forward in the weapon.

The main wall position 26a of the lid is sunk 50 to allow the passage of the feeder projection, and its spacing from the perforated cartridge supporting plate, permits dirt from the interior of the magazine to pass unhindered through the openings in the said plate. In the normal posi- 55

tion of rest (Fig. 1) the lid with the tension lever 26 completely closes the bottom of the magazine.

We claim:—

1. A cartridge magazine for firearms comprising a casing removably attached to the firearm and having an opening for the insertion of a cartridge pack into the casing, a cover for said opening, a cartridge feeder, a tensioning lever for the feeder, means by which the tensioning lever may 5 be urged to open position and the feeder in the direction of the rear end of the casing for refilling the magazine, and a cartridge supporting plate in the magazine casing, said plate having openings for the discharge of empty cartridge 10 clips and for guiding the feeder and further openings leaving only narrow strips for supporting the cartridges and the said feeder tensioning lever being designed as a dust excluding lid spaced below the supporting plate and closing the 15 bottom of the magazine when the tensioning lever is in its normal position.

2. A cartridge magazine for firearms comprising a casing removably attached to the firearm and having an opening for the insertion of a cartridge pack into the casing, a cartridge feeder, a tensioning lever for the feeder, means by which the tensioning lever may be urged to open position and the feeder in the direction of the rear end of the casing for refilling the magazine, and a cartridge supporting plate in the magazine casing, said plate having openings for the discharge of empty cartridge clips and for guiding the feeder and further openings leaving only narrow strips for supporting the cartridges and the said feeder tensioning lever being designed as a dust excluding lid spaced below the supporting plate and closing the bottom of the magazine when the tensioning lever is in its normal position. 5 10 15
